UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

POURING POT USED IN CONNECTION WITH HOT-TOP FEEDERS.

Application filed December 29, 1923. Serial No. 683,497.

To all whom it may concern:

Be it known that BLOOMFIELD H. HOWARD and ERNEST J. TURNER, citizens of the United States, residing, respectively, at Washington, District of Columbia, and Pittsburgh, in the county of Allegheny and State of Pennsylvania, have invented certain new and useful Improvements in Pouring Pots used in Connection with Hot-Top Feeders, of which the following is a specification.

Our invention relates to improvements in pouring pots used in connection with hot top feeders.

15 The object of our invention is to provide a pouring pot with means for supporting it on the upper end of the mold above the feeder or hot top so that the pouring operation into the feeder can readily take place 20 and yet relieve the hot top feeder of the weight of the pot thus lessening the liability of the breaking of the hot top feeder during the pouring operation.

Another object of our invention is to provide 25 a pouring pot which will function with the feeder in preventing seams and holes known as "piping" and also reduce "segregation" to a minimum.

Another object of our invention is to provide 30 a pouring pot adapted to be used in connection with any form of hot top feeders such as shown in our numerous patents and at the same time obtain the above mentioned results.

35 A further object of our invention is to provide a simple, cheap and effective arrangement of this character in which the pouring pot can be readily placed in position or removed and provide certain details of structure and combination of parts 40 hereinafter more fully set forth.

In the accompanying drawings,

Figure 1 is a perspective view of an ingot mold showing the pouring pot with supporting means above the hot top feeder and showing the pouring pot raised from the support.

Figure 2 is a vertical sectional view showing the pot supported by the upper end of the mold above the feeder.

Figure 3 is a top plan view of Figure 2.

Figure 4 is a vertical sectional view of an ingot mold showing a modified form of pouring pot.

55 Figure 5 is a top plan view of Figure 4.

Figure 6 is a top plan view of an oblong pouring pot.

Figure 7 is a top plan view of an ingot mold showing a corrugated hot top feeder with the pouring pot supporting means in 60 position.

Figure 8 is a perspective view of an ingot mold showing a modified form of supporting means for the pouring pot.

Figure 9 is a vertical sectional view of 65 the supporting means shown in Figure 8 and showing the pouring pot thereon.

Figure 10 is a vertical sectional view of 70 an ingot mold showing a modified form of pouring pot support.

Figure 11 is a perspective view of the upper end of the ingot mold showing our improved feeder and showing a further modified form of pouring pot supporting means.

Figure 12 is a transverse sectional view 75 of the form shown in Figure 11 and showing the pouring pot in position thereon.

Figure 13 is a vertical sectional view of the upper end of the ingot mold showing 80 our improved shoulder feeder and showing a modified form of pouring pot and the support therefor.

Referring now to the drawings and particularly to Figure 1, 1 represents the ingot 85 mold which as shown is a circular form and having the hot top feeder supported at its upper end by means of the ribs 3 all of which is well understood and while we have shown this specific form of hot top feeder it 90 will be understood that our invention is adapted to be used on any mold where the hot top feeder extends above the upper end thereof.

Resting upon the upper edge 4 of the 95 mold are the feet 5 carried by the standards 6 which extend upwardly along the outer periphery of the feeder and have their upper ends turned inwardly as indicated at 6' and which have secured to their lower faces the 100 frame 7. This frame as shown is made of sections riveted together and adapted to hold the standards together all of which form a frame adapted to slip over the upper end of the feeder.

105 The pouring pot 8 is of a cylindrical form having its lower end provided with an inwardly extending flange 9 which rests upon the inwardly turned ends 6' of the standards and whereby the pouring pot is supported 110

above the hot top feeder in its proper position, yet the weight of the pouring pot is taken off the upper end of the hot top feeder as clearly shown in Figure 2 of the drawings. The pouring pot is provided on opposite sides with lugs 10 by means of which it can be placed on and removed from the mold all of which is well understood in the art. The pouring pot is provided with a 10 lining 11 of refractory material which rests upon the upper face of the flange 9, said flange extending inwardly beyond the said lining. Resting upon the flange 9 on the inside of the lining 11 is the pouring plate 12. This plate 12 is provided with a series 15 of openings 13 therein, whereby the metal passes from the pouring pot into the feeder in small streams.

In Figure 4 the mold 1 and the pouring 20 pot supporting means 14 are constructed the same as that shown in Figures 1, 2, 3 and 4 of the drawings. The pouring pot 15 in this form is provided with a narrow inwardly extending flange 16 adapted to support the refractory lining 17 and the lower 25 end of said lining is drawn inwardly forming the beveled wall 18. The pouring plate 19 is provided with a beveled outer edge 20 whereby the pouring plate is supported in the pot by the refractory lining.

In Figures 8 and 9 the pouring pot supporting means comprises a plate 20 of the shape to correspond to that of the feeder and extends outwardly beyond the outer periphery thereof and is provided with a series 35 of legs 21 adapted to rest upon the upper end of the mold 1. The pouring pot 22 rests upon the plate 20 as clearly shown in Figure 9 of the drawings. In this form the pouring pot 22 is constructed exactly like that shown in Figure 4 of the drawings.

In the modification shown in Figure 10 of the drawings the pouring pot supporting means is a plate 23 having legs 24 supported in the same manner as that shown in Figure 45 9. The outer edge of the plate 23 is turned upwardly forming an annular flange 25 adapted to engage the outer periphery of the pouring pot 26. In this form the pouring pot is made of a greater diameter than that of the feeder so as to provide for the flange 25 on the outside of the supporting legs.

In Figures 11 and 12 in order to support the pouring pot we have provided two strips 55 of metal 26 and 27 having the downwardly extending portions 28 and 29 which extend down along the outer wall of the feeder 30 and are provided at the lower ends with the feet 31 and 32 which rest upon the upper 60 end of the mold 1. In this form the pouring pot 32 rests upon the strips 26 and 27 which are supported thereby above the feeder. In this form the pouring pot is exactly like that shown in Figure 9.

65 In Figure 13 we have shown a metal plate

33 of a shape approximately that of the upper edge of the feeder 34 and resting thereon. This form of support is more particularly adapted for feeders in which the upper ends are provided with a large annular flange 70 for supporting the same in the upper end of the mold. In this form the pouring pot 35 is constructed like that shown in Figure 12 except that the pouring plate 36 is slightly conical, extending a slight distance into the upper end of the feeder, this plate 36 like the pouring plates of the other forms is provided with a series of openings 37 preferably conical in shape with the larger opening 75 within the pouring pot.

Having thus fully described our invention what we claim is:—

1. A pouring pot support comprising a frame adapted to support the pouring pot, and means carried by the frame for supporting the same on the mold. 85

2. A pouring pot support comprising a frame adapted to support a pouring pot, a hot top feeder, and means carried by the frame for supporting the same on the mold. 90

3. A pouring pot support comprising legs supported by the mold and extending over the upper edge of the hot top feeder and adapted to support the pouring pot above the feeder. 95

4. The combination with an ingot mold having a feeder and means for supporting a pouring pot above the feeder.

5. The combination with an ingot mold having a feeder and means supported by the upper end of the ingot mold for supporting a pouring pot above the feeder. 100

6. The combination with an ingot mold having a feeder in its upper end and extending above, and means supported by the upper end of the mold for supporting a pouring pot above the upper end of the feeder. 105

7. The combination with an ingot mold having a feeder, means supported by the upper end of the ingot mold and extending over the upper edge of the feeder and a pouring pot supported by said means, above the upper end of the feeder. 110

8. The combination with an ingot mold having a feeder extending above the upper end of the mold a frame extending over the upper edge of the feeder and having legs resting upon the upper end of the mold and a pouring pot resting upon said frame above the upper end of the feeder. 115

9. The combination with an ingot mold having a feeder extending above the upper end, means supported by the upper end of the ingot mold and extending above the upper edge of the feeder and a pouring pot resting upon said means, and comprising a metal body portion having a refractory lining and a removable pouring plate. 120

10. A combination with an ingot mold having a feeder extending above the upper 125 end

- end of the mold, a frame above the upper edge of the feeder and having legs extending downwardly and supported by the upper end of the mold, a pouring pot comprising a metal body portion resting upon the frame, a refractory lining for said body portion and a removable refractory pouring plate in the lower end of the pot and having a series of openings therein.
- 10 11. A combination with an ingot mold having a feeder extending above its upper end of the mold, a frame above the upper edge of the feeder and having legs extending downwardly and supported by the upper end of the mold, a pouring pot comprising a metal body portion resting upon the frame and having a refractory lining and a pouring plate of refractory material removably supported in the pot and having a series of openings therein.
- 15 12. A combination with an ingot mold having a feeder extending above the upper end of the mold, means supported by the upper end of the mold and extending across the upper edge of the feeder and a pouring pot supported by said means above the feeder.
- 20 13. A combination with an ingot mold having a feeder extending above the upper edge of the mold, means supported by the upper end of the mold and extending over the upper edge of the feeder, a metal pouring pot having an inwardly extending flange resting upon said means for supporting the same above the feeder, a refractory lining carried by the pot and supported by the flange, and a removable pouring plate supported by the flange and having a series of openings therein.
- 25 14. A combination with an ingot mold having a feeder extending above the upper end, means supported by the upper end of the mold and extending across the upper edge of the feeder, a metal pouring pot having an inwardly extending flange at its lower edge resting upon said means, a refractory lining supported by said flange and having its lower end tapered inwardly and a pouring plate supported by said tapered lower end and having a series of openings therein.
- 30 15. A pouring pot support for ingot molds comprising legs adapted to rest upon the upper edge of the mold and having portions extending across the upper edge of the feeder for supporting a pouring pot.
- 35 16. A pouring pot support comprising legs adapted to rest upon the upper end of the mold and a frame carried thereby and extending across the upper edge of the feeder and adapted to support a pouring pot above the feeder.
- 40 17. A pouring pot support comprising a frame above the upper edge of the feeder and adapted to support a pouring pot and legs carried thereby and adapted to support the same upon the upper edge of the mold.
- 45 18. A pouring pot support comprising a frame above the upper edge of the feeder having an upwardly extending flange forming a support for a pouring pot and legs carried by the frame and adapted to be supported by the upper edge of the mold.
- 50 19. The combination with an ingot mold of a feeder extending above the upper edge, a frame above the upper edge of the feeder and having an upwardly extending flange, a pouring pot resting upon the frame and held thereon against lateral movement by the flange and legs carried by the frame and resting upon the upper edge of the mold for supporting the frame above the upper edge of the feeder.
- 55 20. A pouring pot support comprising a metal plate supported by the upper end of the feeder and adapted to support a pouring pot.

In testimony whereof we affix our signatures.

BLOOMFIELD H. HOWARD.
ERNEST J. TURNER.
